CLAIM

The ornamental design for an exterior surface configuration of a vehicle light, as shown and described.

DESCRIPTION

FIG. 1 is perspective view from the front right of an exterior surface configuration of a vehicle light. The drawings and descriptions represent the right side embodiment. The design also contemplates a mirror symmetrical embodiment on the left side of the vehicle. The dash line included denotes environment and is not part of the claimed design

FIG. 2 is a front elevation view thereof;

FIG. 3 is a right elevation view thereof; and,

FIG. 4 is a top view thereof.

1 Claim, 4 Drawing Sheets

FIG. 1

FIG. 2

FIG. 4
